ATTORNEY

UNITED STATES PATENT OFFICE.

LEONARD FRIEDBERG, OF BROOKLYN, NEW YORK.

POWDER-PUFF HOLDER AND LOOSE-POWDER CONTAINER.

Application filed April 6, 1927. Serial No. 181,488.

The present invention is concerned with the provision of an improved type of container for loose powder, and an associated applicator such as the usual powder puff.

5 Previous devices designed for this purpose have been for the most part in the nature of metal boxes. They have not only been awkward to use and refill, but the ever present danger of spilling the powder has 10 acted as a deterrent to their extensive use. Most of them have been quite liable to the inconvenience of spilling powder about in a handbag while being transported, or of spilling powder over the user when the 15 covers are opened. They have been subject to the further disadvantage of requiring the use of a very small flat powder puff which quickly becomes matted and unsightly.

In accordance with the present invention, 20 I provide a powder container and powder puff carrier in the nature of a bag of the general envelope type, one of the walls of the bag being preferably hollow and serving as a powder container, and the powder puff 25 being carried in the main pocket of the bag and receiving powder through a filter covering the opening in the inner face of the hollow wall.

By virtue of this construction, any powder which escapes from the powder compartment will adhere to the powder puff, and when the puff is withdrawn there will be no danger of spilling powder about. The powder is maintained in a highly sanitary condition, and the powder compartment may be readily refilled.

Among more general objects of the invention may be noted the provision of a container of the above described character which 40 will be neat and attractive in appearance, simple and practical in construction, rugged, durable and efficient in use, and well suited to the requirements of economical manufacture and facile manipulation.

45 With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a perspective view showing the

powder and powder puff carrier embodying 55 the present invention with the cover flap closed.

Fig. 2 is a similar view looking at the opposite side of the bag with the cover flap folded back and the powder compartment open for filling.

Fig. 3 is a longitudinal sectional view taken approximately on the line 3-3 of Fig. 1.

Fig. 4 is a similar view, but showing the 65 mouth of the powder compartment folded over and snapped shut, and the flap of the bag also folded over and snapped.

Fig. 5 is a sectional view taken approximately on the line 5-5 of Fig. 4. 70

In the drawings I have shown a device of the general envelope type including a rear wall 10 and a double front wall 11, 12 connected at their bottom and side edges to cooperatively define a pocket 13 in which 75 a powder puff 14 may be carried. The two flexible members which constitute the double or hollow front wall of the bag are also connected together at their lateral and bottom edges, extending well above the top of 80 the back member 10 as seen in Figs. 2 and 3 and being unconnected at their top, whereby a receiving mouth 15 is formed, through which loose powder may be introduced into the compartment defined by members 11 and 85 12. The mouth end of the wall 11, 12 preferably carries at its outer face a snap fastener element 16 adapted to coact with a mating element 17 mounted on the inner face of the wall 11 at a point below the top of 90 the section 10. Preferably the upwardly projecting mouth end of the double front wall or powder compartment is rolled over twice, and the snaps 16 and 17 buttoned together, as best seen in Fig. 4, so that the 95 escape of powder through the filling opening 15 is prevented.

Wall 11 is provided with a powder dispensing opening 18 therein covered by a sheet of gauze or similar filter material 19, 100 so that powder may escape from the powder compartment on to the puff within the pocket 13. In the ordinary course of handling the container, a certain amount of powder may filter on to the puff, or the bag 105 may be lightly tapped to cause passage of powder through the gauze when it is desired to apply the powder.

Preferably integrally connected to the upper edge of the rear wall 10 is a flap 20 adapted to fold over the front wall 11, 12 of the container and carrying a snap fastener element 21 for engagement with a mating element 22 on the outer face of the front wall 12.

Inasmuch as it is always desirable to have a mirror handy when applying powder to the face, I preferably mount a mirror 25 on the inner face of the flap 20.

The entire bag is preferably made of some material which is impervious to the passage of powder, such for instance as a rubberized fabric. When filling the powder compartment, snaps 16 and 17 are disengaged and the mouth of the powder chamber unfolded to the position of Fig. 2, in which position powder may be introduced through the filling opening 15, the upper flap portion of the front wall 11, 12 is then folded over and buttoned down. When the device is carried in a bag or the like, or in the hand, the

cover flap 20 is ordinarily buttoned down as shown in Fig. 1.

Various changes and alterations might be made in the general form and arrangement of the parts described without departing from the invention. Hence I do not wish to limit myself to the details set forth, but shall consider myself at liberty to make such changes and alterations as fairly fall within the spirit and scope of the appended claim.

I claim:

An envelope type container including front and rear walls defining a pocket adapted to receive a powder puff, and a flap carried by the rear wall adapted to be folded over and secured to the outer face of the front wall, said forward wall being hollow for the reception of loose powder and having a screened opening in its inner face through which powder is adapted to filter to the puff.

LEONARD FRIEDBERG.
